Patented Feb. 3, 1920.

UNITED STATES PATENT OFFICE.

AARON HILL, OF LOS ANGELES, CALIFORNIA.

LUBRICATING DEVICE FOR GANG-DRILLS.

1,329,663.

Specification of Letters Patent.

Patented Feb. 3, 1920.

Application filed September 13, 1917. Serial No. 191,256.

To all whom it may concern:

Be it known that I, AARON HILL, a citizen of the United States, residing at Los Angeles, in the county of Los Angeles and 5 State of California, have invented a new and useful Lubricating Device for Gang-Drills, of which the following is a specification.

This invention relates to the feeding of 10 lubricant to drills used upon a machine such as is shown and described in Letters Patent of the United States, No. 1,133,243 granted to me on the 23rd day of March, 1915.

In machines of this type a series of drills 15 are movably mounted upon a suitable support so that the drills may be spaced apart according to the work to be performed and it is the main object of my invention to provide a device whereby lubricant may be fed 20 to the drills during operation of the same regardless of the relation of the respective drills to each other. Other objects and advantages will appear hereinafter from the following description.

25 Referring to the drawings which are for illustrative purposes only:

Figure 1 is an elevation of a gang drill showing a lubricating device thereon embodying a form of my invention.

30 Fig. 2 is an enlarged side elevation partly in section of a part of one of the drill units shown in Fig. 1.

Fig. 3 is an enlarged elevation of the device shown in Fig. 2.

35 Fig. 4 is an enlarged sectional view on line 4—4, Fig. 2.

Fig. 5 is an enlarged side elevation of a 40 drill unit provided with a modified form of my invention, part of the same being shown in section, and

Fig. 6 is a front elevation of the device shown in Fig. 5.

The gang drill in general consists of a frame having vertical members or posts 11, 45 longitudinal beams 12 and 13, the beam 13 being a horizontal support upon which is slidably mounted a series of drill units 14. 15 designates a vertically movable table for supporting the work, the table being supported in any suitable manner in the frame 50 of the machine. Each drill unit 14 is provided with a suitable drill 16 mounted therein, and each drill unit 14 is provided with a downwardly extending arm 17 provided 55 with a boss 18 in which is mounted a hollow shaft or conductor 19, the shaft 19 being in-

clined at an angle and the lower end of the same extending to a point adjacent to the drill 16.

20 designates a hub or sleeve mounted on the shaft 19, provided with a circular flange or plate 21 secured to the inner end of the same, such plate 21 abutting against the boss 18 and forming a splash guard. Arranged on the outside of the plate 21 is a series of 60 elevators 22 each consisting of a curved pipe, the outer end of which is cut off as indicated at 23 on a line radial to the center of the shaft 19. The inner end of each elevator extends into the hub 20 connecting with an 65 opening or duct 24 which extends to the shaft 19. The shaft 19 is provided with an opening or passage 25 in alignment with the ducts 24 so that any liquid in the elevators in proper position will be fed from the 70 elevator to the interior of the shaft 19.

75 Mounted on each hub 20 is a sprocket wheel 26 which is engaged by a sprocket chain 27, the sprocket chain 27 being secured at its ends to quadrants 30 and 31 pivotally 80 mounted at 32 and 33 to the uprights 11 of the machine. A reciprocating movement is given the chain 27 by an arm 35 pivotally connected to an extension 36 on the quadrant 31, the arm 35 being connected to a crank 37 85 on a shaft 38 driven by means of a beveled gear 39 from a similar gear 40 secured to a pulley 41 which is driven from any suitable power source not shown. 42 designates a coiled spring mounted on a bracket 43 and 90 secured to the quadrant 30 for placing an elastic tension on the chain 27.

95 The operation of the form of device shown in Figs. 1 to 4 inclusive is as follows:

The drill units being spaced upon the beam 13 in the desired position and being secured thereon in any suitable manner, the machine is started and through the connections heretofore described, the chain 27 is reciprocated back and forth by the action of 100 the quadrants 30 and 31. The elevators on each drill unit extend into a pan or reservoir 44 in which is placed the lubricating liquid indicated at 45. The movement of the chain 27 is sufficient to cause the elevators to move through an arc of more than 105 half a circle so that as they are moved in the liquid any of the elevators extending into the liquid take up some of the liquid, and as such elevator reaches its upper position such liquid runs through the elevator 110 to the duct 24 and through the opening 25

in the shaft where it is delivered through the shaft to its associated drill.

It is to be noted that the elevators on the adjacent drills are staggered as indicated in Figs. 2 and 3 so that the elevators on adjacent drills may pass each other to a certain extent thereby permitting a closer adjustment of the drills than would otherwise be the case.

In the form of device shown in Figs. 5 and 6, the arm 17 on the drill unit 14 is provided with a hollow shaft 50, the outer end of which is provided with a pin 51 upon which is movably mounted an elevator 52, the elevator 52 consisting of a trough 53, the outer end 54 of which extends into the liquid 55 in a pan 56 and the inner end of which is bent downwardly as indicated at 57 and terminates over an opening 58 formed in the top of the shaft 50. 60 designates an arm extending downwardly from the elevator 52 into the path of a series of cams 63 formed on the side of a sprocket wheel 64, the sprocket wheel being driven by a sprocket chain 65 in the same manner as heretofore described with respect to the chain 27 illustrated in Figs. 1 to 4 inclusive.

The operation of the device shown in Figs. 5 and 6 is as follows:

The sprocket chain being reciprocated causes the arm 60 on the elevator to be swung forwardly and rearwardly due to riding over the cams 63 on the sprocket wheel, such forward movement raising the outer end of the elevator as indicated in dotted lines in Fig. 5 so that the liquid caught therein runs down and rearwardly on the elevator and is delivered through the opening 58 into the shaft 50, running through the shaft 50 and 40 being delivered on the drill 16.

What I claim is:

1. A lubricating device for gang drills of the type in which the drills are independently movable comprising a conductor for each drill, an elevator for each conductor, and a lubricator container common to all of said elevators and within which the several elevators are movable as the drills are positioned variably with relation to each other.

2. A lubricating device for gang drills comprising a conductor for each drill, a rotatable elevator for each conductor, a lubricator container common to all of said eleva-

tors, and an operating means for said elevators common to all of the elevators, said operating means consisting of a driven member on each elevator and a driving member common to all of said driven members.

3. A lubricating device for gang drills comprising a conductor for each drill, an elevator for each conductor, the respective elevators being arranged in staggered relation to each other, and a lubricator container common to all of said elevators, each drill, conductor and elevator constituting a unit, said units being movable independently for relative adjustment along the container, and an operating means for said elevators common to all of the elevators.

4. A lubricating device for gang drills comprising a conductor for each drill, a rotatable elevator for each conductor, a lubricator container common to all of said elevators, and an operating means for said elevators common to all of the elevators, said operating means comprising a sprocket wheel in fixed relation to each elevator and a driven chain engaging said sprocket wheels.

5. In combination a support, a series of drill units movably mounted on the support, a conductor for each drill unit, an elevator for each conductor, said elevators being arranged in staggered relation to each other, a lubricator container common to all of said elevators and in which the elevators are movable, and operating means for said elevators common to all of said elevators.

6. In combination, a support, a series of drill units movably mounted on said support, a hollow shaft fixed in each unit having a lubricator receiving opening therein, an elevator rotatably mounted on each shaft, said elevator consisting of a sleeve rotatably mounted on the shaft, a series of curved pipes extending outwardly from said sleeve and communicating through openings in said sleeve with the opening in the shaft, a sprocket wheel on each sleeve, a chain engaging the sprocket wheels and means for reciprocating said chain to operate the sprocket wheels.

In testimony whereof I have hereunto set my hand at Los Angeles, California, this 7th day of September, 1917.

AARON HILL.
